DESIGN FOR TOASTED BREAD

William H. Brooks, Fairfax, Calif.

Application April 27, 1936, Serial No. 62,320

Term of patent 14 years

To all whom it may concern:

Be it known that I, William H. Brooks, a citizen of the United States, residing at Fairfax, county of Marin, State of California, have invented a new, original, and ornamental Design for Toasted Bread, of which the following is a specification, reference being had to the accompanying drawing, forming part thereof.

Fig. 1 is a front view of a piece of toast showing my new design.

Fig. 2 is an enlarged sectional view taken on line II—II of Fig. 1.

The side of the piece of toast not shown is practically identical with the front view, as shown in Fig. 1.

I claim:

The ornamental design for toasted bread, substantially as shown and described.

WILLIAM H. BROOKS.
